UNITED STATES PATENT OFFICE

WILLIAM J. MORSE, OF ATTLEBORO, MASSACHUSETTS, ASSIGNOR TO MORSE ANDREWS COMPANY, OF ATTLEBORO, MASSACHUSETTS, A CORPORATION OF MASSACHUSETTS

DESIGN FOR A BUCKLE

Application filed March 6, 1930. Serial No. 34,752. Term of patent 3½ years.

To all whom it may concern:

Be it known that I, WILLIAM J. MORSE, a citizen of the United States of America, residing at Attleboro, county of Bristol, State of Massachusetts, have invented a new, original, and ornamental Design for a Buckle, of which the following is a specification, reference being had to the accompanying drawing, forming a part thereof.

Fig. 1 is a top plan view; Fig. 2 is a section on the line 2—2 of Fig. 1; and Fig. 3 is a section on the line 3—3 of Fig. 1 of a buckle, showing my new design.

I claim:

The ornamental design for a buckle, substantially as shown.

WILLIAM J. MORSE.
